CLAIM

(22) **Filed:** Mar. 9, 2013

The ornamental design for a sound processor enclosure exterior, as shown and described.

(51) **LOC (9) Cl.** 24-99

DESCRIPTION

(52) **U.S. Cl.**

FIG. 1 is a top isometric view of a sound processor enclosure exterior showing the new design,

USPC D24/174

FIG. 2 is a bottom isometric view thereof,

(58) **Field of Classification Search**

FIG. 3 is a front view thereof,

USPC D24/173-175, 151; D14/205, 206,
D14/223-226, 249; 381/23.1, 312,
381/322-324, 328, 330, 380, 381; 181/135

FIG. 4 is a rear view thereof,

See application file for complete search history.

FIG. 5 is a right side view thereof, and the left side view is

(56) **References Cited**

identical,

FIG. 6 is a top view thereof,

U.S. PATENT DOCUMENTS

FIG. 7 is a bottom view thereof,

1,422,877 A 7/1922 Maxfield
4,248,237 A 2/1981 Kenny
4,347,956 A 9/1982 Berger
4,419,995 A 12/1983 Hochmair et al.
4,456,797 A 6/1984 Olsen
4,532,930 A 8/1985 Crosby et al.
4,545,381 A 10/1985 Bourney
4,562,590 A 12/1985 DeLage
4,584,718 A 4/1986 Fuller
4,682,363 A 7/1987 Goldfarb et al.
4,683,587 A 7/1987 Silverman
4,727,599 A 2/1988 Rappaport et al.

FIG. 8 is a top isometric view of another sound processor enclosure exterior showing the new design,

FIG. 9 is a bottom isometric view thereof,

FIG. 10 is a front view thereof,

FIG. 11 is a rear view thereof,

FIG. 12 is a right side view thereof, and the left side view is
identical,
FIG. 13 is a top view thereof; and,
FIG. 14 is a bottom view thereof.

The broken line showing of an electrical connector is for the
purpose of illustrating portions of the article that form no part
of the claimed design.
